Frank B. Cook.

UNITED STATES PATENT OFFICE.

FRANK B. COOK, OF CHICAGO, ILLINOIS.

ELECTROTHERMAL CUT-OUT.

No. 845,219.

Specification of Letters Patent.

Patented Feb. 26, 1907.

Application filed April 16, 1906. Serial No. 311,992.

To all whom it may concern:

Be it known that I, FRANK B. COOK, a citizen of the United States of America, residing at Chicago, in the county of Cook and State 5 of Illinois, have invented a new and useful Electrothermal Cut-Out, of which the following is a specification, reference being had to the accompanying drawings, illustrating same.

10 My invention relates to electrothermal protectors for protecting electrical circuits and apparatus from abnormally-large currents of electricity, and especially to such protectors adapted to protect the circuits and apparatus 15 from small increments of electrical currents generally termed "sneak-currents."

The principal objects of my invention are to provide an electrothermal protector of this class which is held in operative position by 20 non-conducting cementing material and to arrange the actuating means to close the electrical circuit through the protector without depending upon the cementing material.

This present invention is an improvement 25 on my copending application for Letters Patent on electrical protective apparatus filed March 8, 1906, Serial No. 304,929.

It is generally customary to provide an electrothermal protector with a metallic 30 solder for securing certain portions thereof against operation, the solder being softened by heat produced in the device by an abnormally-large current of electricity to allow the apparatus to operate, and also forming part 35 of the conductive circuit. In this present invention I arrange the parts so that the electrical circuit through the device is completed without depending upon the cementing material and hold the parts in operative position by non-conducting cement or wax, 40 which is softenable by heat produced in the device, to allow the apparatus to operate.

Referring to the accompanying drawings, illustrating the preferred form of my invention, Figure 1 is a side view of the protector of the invention in connection with its supporting and operating members. Fig. 2 is a plan view of Fig. 1 with an end portion of the protector removed.

45 Like characters refer to like parts in the several figures.

The heating element preferably used comprises a piece of carbon or graphite 1, to which are properly secured conducting end

5 caps 2 and 3. In securing the end caps 2 and 3 to the heating element 1 the latter is preferably metallically plated on the ends and the caps soldered thereto by hard solder. End cap 3 is provided with a stem 4, which is threaded and screwed into a threaded portion 5 of a supporting member 6. This threaded connection firmly holds the protector in place at all times. The end cap 2 is provided with a neck portion 7 and a head 8 thereon, forming an annular recess adapted 65 to receive the free end 9 of spring member 10. The free end 9 of spring member 10 is split, as at 11, and formed so as to grip the neck portion 7 when spring 10 is engaged with the protector, as shown in Fig. 1. The split 7c end 9 of spring 10 enables the free end 9 of spring 10 to spring apart somewhat when engaged with the protector; and thereby firmly grip the neck portion 7 and make a good electrical connection therewith. The free end 9 of spring 10 also 75 preferably bears against the end of cap 2, which also helps to make an electrical connection between the spring 10 and the protector.

80 The free end 9 of spring 10 does not grip the neck portion 7 sufficiently to hold spring 10 in a set position against its tension without assistance. To assist in holding spring 10 in this set position, as shown in Fig. 1, I provide an insulating cementing material 12, 85 such as a softenable wax, between the head 8 and portion 9 to adhere to these portions and hold spring 10 in a set position when the wax 12 is cool. When the wax 12 is heated, however, it becomes soft, and thereby allows 90 spring 10 to separate from the protector and take the position 13. (Shown in dotted lines in Fig. 1.) When this protector is used in connection with telephone - switchboard apparatus, the spring 10 is preferably connected through a conductor 14 to the switchboard, and support 6 is preferably connected through a conductor 15 to the line. It will be seen that when the device operates the circuit is opened between the switchboard 100 and line at the protector, which entirely disconnects the switchboard from the objectionable current coming from the line.

105 The operation of the device is as follows: When an abnormally large current of electricity traverses the heating element 1 for a sufficient length of time, depending upon the strength of the current, it produces heat in 1,

which heat is conducted to the softenable cementing material 12 to soften same. When the cementing material 12 is sufficiently softened, it releases its hold upon spring 10 and allows the latter to separate from the neck portion 7 and take the position 13, which opens the circuit through the protector. When the protector cools, the wax 12 becomes hard and nearly fills up the recess at 10 the end of the protector, especially on the side from which spring 10 was pulled. As this recess is now partially obstructed, spring 10 cannot be set entirely back to operative position unless the wax is heated or 15 unless it is forced through the wax.

It will readily be seen that this protector may be operated again when properly reset. In resetting the protector it is only necessary to reheat the wax 12, push the spring 10 back 20 to reset position and hold same there until the wax cools. A convenient way of accomplishing the resetting of this device is to apply a resetting-tool thereto in a manner similar to that described in my copending application above mentioned.

It is not believed to be necessary to here describe the resetting of the protector in detail, as this is fully done in the said copending application. It is believed to be sufficient here to merely show that the protector 30 can be reset and reoperated, in fact, as many times as desired.

I do not wish to limit this invention to the particular details of construction as herein shown or to any any particular insulating wax or cementing material. As a cementing material beeswax, Japanese wax, shellac, palm-tree wax, stearin, paraffin, or resin may be used with very satisfactory results.

40 What I claim as my invention, and desire to secure by Letters Patent, is—

1. A thermal protector comprising a piece of homogeneous resistance material, suitable end caps therefor and secured thereto, a 45 suitable support connected to one of the end caps by a screw connection, an operable spring member electrically connected with the other end cap by bearing against same, and insulating-wax securing the said spring member to its end cap.

2. An electrical protector comprising a heating element, a terminal cap therefor, a spring member engaging the terminal cap, a split in the spring member to allow the latter 5 to firmly grip a portion of the terminal cap,

and insulating cementing material normally holding the spring member in connection with the terminal cap.

3. A thermal protector comprising a heating element, a terminal therefor, a spring member provided with a slotted split portion adapted to bear against and grip a portion of the terminal, and heat-susceptible insulating cementing material normally holding the spring member in connection with the terminal.

4. A thermal protector comprising a heat-producing element, means for securely supporting same, a terminal cap for the heating element provided with a small neck portion and a head to form an annular recess, a spring member provided with a slot adapted to fit over the neck portion, and a split extending from the bottom of the slot to allow the spring member to firmly grip the neck portion in the slot to make good electrical connection therewith, and heat-susceptible insulating material in the said recess normally holding the spring member in place in connection with the said neck portion, when cool.

5. A thermal protector comprising a piece of graphite and a metallic terminal on each end thereof, a spring-support for the protector, a threaded portion on one said terminal 85 making screw connection with the said support, an annular recess on the other said terminal, a spring member the free end of which bears against the last-mentioned terminal so as to make electrical connection therewith, and heat-susceptible insulating material in the annular recess normally holding the spring member in connection with its terminal.

6. An electrothermal protector comprising 95 heat-producing means and means for securely mounting same, a terminal for the heat-producing means provided with an annular recess, a spring member engaging the terminal in the annular recess, and heat-susceptible insulating material in the annular recess normally holding the spring member therein.

As inventor of the foregoing I hereunto subscribe my name, in the presence of two subscribing witnesses, this 12th day of April, 1906.

FRANK B. COOK.
